VERTICAL WALL LOUVER

Freeland H. Leslie, Chicago, Ill.

Application October 31, 1941, Serial No. 417,341

3 Claims. (Cl. 189—63)

This invention relates to vertical wall louvers. More particularly, it has to do with that type of vertical wall louver having an exterior frame with a set back peripheral flashing.

Vertical wall louvers are of two types. The flush type has a flashing around the outside front edge of the louver for mounting the louver flush with whatever surface engages the flashing, as, for example, the wood sheathing of a house. In order to protect the flashing from the weather, it is customary to lay the siding over the flashing and thereby expose the ends of the siding. Such a job has an unfinished external appearance and frequently a wooden frame or casing is built. In the case of steel louvers, there has been developed a self-framing wall louver which is characterized by a peripheral flashing set back from the front edge of the louver casing so that the louver will project forwardly of the sheathing of the house. Additionally, a facing strip is provided for the face of the louver. By this construction the ends of the siding may be laid flush with the side of a facing strip and it is in consequence unnecessary to frame the louver with a wooden frame in order to make it attractive.

One objection to exteriorly cased vertical wall louvers now on the market lies in the fact that the vertical facing strips which contribute to the pleasing exterior appearance by giving exteriorly a casing or frame appearance are turned inwardly over the vanes of the louver. Because these vanes extend to the forward edge of the louver, at each of their ends they engage these vertical facing members and create pockets within which collect dirt, leaves and the like. While dirt and leaves collected in these pockets are unsightly in themselves, the principal objection to them resides in the fact that during a rain the dirt runs down the front of the louver and then makes a streak down the house wall. One object of this invention is to obtain this casing appearance by turning the vertical facing members outwardly without sacrificing beauty or strength of construction. A feature of this invention contributing toward this end is the employment of a spaced double wall for each of the vertical sides of the louver. These two walls are spaced by whatever distance is thought desirable for the width of the facing strips and then the outer vertical wall is bent at any suitable distance away from the louver to form the flange.

Another objection to existing vertical wall louvers resides in the fact that the lowermost vane which constitutes the sill of the louver drains across a vertical surface which terminates

in a horizontal surface leading back to the lower or bottom flashing of the louver. There is a tendency of water to run along the underside of this flat edge to the flange and then downwardly behind the siding. Another object of this invention, therefore, is to provide a recess between the bottom or dripping edge of the lowermost vane and the bottom flashing whereby water can only reach the flashing by first moving upwardly before it can travel horizontally to the flashing. By this arrangement all water shed by the louver is forced to drip off the dripping edge.

Another object of this invention is to provide a new and improved means of assembling the lowermost vane with the vertical side walls of the louver so as to prevent seepage of water to the inside of the louver. Generally speaking, building specifications do not call for a louver sold at a price such that soldering of joints is warranted.

For the most part these vertical wall louvers are spot welded only and joints are not watertight. In assembling the vanes with the vertical walls it is customary to flange down or flange up the sides of the vanes and spot weld the flanges thus formed to the side walls. It is apparent that seepage of water between the ends of the vanes and the side walls is possible. It is also clear that such seepage is immaterial excepting in the case of the lowermost vane.

One of the features of this invention is the cutting of the bottom of the vertical side walls of the louver at the same angle as the slope of the vanes and then flanging the two sides of the lowermost vane (that is the sill) upwardly. The flanges are then placed on the outside of the bottom edges of the vertical wall members so that the sill is a trough for carrying off the water. The inside surface of the two vertical side wall members drain into the trough-like sill and all seepage of water within the house is avoided. Moreover, soldering is unnecessary.

As will also appear hereinafter, the applicant employs a double spaced wall fabricated from two pieces of metal. By this arrangement it is possible to spot weld the vanes to the inner wall before adding the outer wall. In so doing, visible welds which are unsightly even when painted are reduced to a minimum.

These and such other objects as may herein-after appear are obtained in one embodiment of the invention shown in the accompanying drawing, wherein:

Figure 1 is a perspective view of the invention having certain parts cut away;

Figure 2 is a front view in elevation of applicant's louver; and

Figure 3 is an enlarged vertical cross-section, the central portion being cut away, taken on the line 3—3 of Figure 2.

Continuing to refer to the drawing and particularly to Figure 1, the casing or frame of applicant's louver consists of two vertical wall members 10 and 12, a top or lintel member 14 and a sill member 16. The vertical wall members 10 and 12 are left and right, the left hand member 10 having a vertical facing strip 18 formed by flanging over the front of the wall member to substantially right angles with the main body portion. Additionally, this forward edge of the member 10 is bent backwardly to form the flange 20. The other vertical wall member 12 similarly has a front facing strip 22 and a vertical flange 24. The bottom of the two vertical wall members 10 and 12 is cut at an angle commencing at the lower front or flange side of each and extending upwardly toward the rear. In applicant's louvers the vanes are at an angle of 45° with the horizontal and consequently this diagonal bottom edge of the two vertical wall members 10 and 12 forms an angle of 45° with the vertical edge of either member.

The lintel or top member 14 has at each end a downwardly directed flange, such as 26, whereby the lintel 14 may be spot welded to the vertical wall members 10 and 12. The sill 16 has two upwardly directed flanges, such as 28, and a downwardly depending apron 30. The corners of the flanges, such as 28, and the upper edge of the apron, such as 32, are suitably sheared to provide ample clearance for quick assembly.

The vertical wall members 10 and 12 are assembled to the lintel 14 and the sill 16 by means of the flanges, such as 26 and 28, which are spot welded as shown.

Having the framework, the vanes are next added. Referring to Figure 3, each vane has a main body portion 34 with a hemmed depending apron 36 and a water baffle at the upper end 38. Each water baffle has a forwardly projecting edge 40. A flange 42 is formed at each end of the vane, applicant preferring to turn the flange downwardly rather than upwardly because of the improved exterior appearance. Each vane is assembled with the side walls 10 and 12 by spot welding these flanges to the side walls. The vanes slope from the back to the front, applicant using a 45° angle with the horizontal. The vanes are so spaced that the water baffle 38 and forwardly projecting edge 40 of one vane is above the depending apron, such as 36, of the vane above.

The peripheral flange around the louver consists of four members, two vertical angulate members 44 and 46, referring now to Figure 1, a top flashing 48 and a bottom flashing 50. The angulate members 44 and 46 are spot welded to the flanges 20 and 24 of the side wall members 10 and 12. That wall of the angulate members 44 and 46 which acts as a flashing has an upwardly extending portion, such as 52, to which the flashing member 48 is spot welded. The flashing member 48 has formed integral therewith a forwardly extending cover 54 and a downwardly directed flange 56. This flange 56 is spot welded to the facing strips 18 and 22, the flanges 20 and 24 and the adjoining wall of the angulate members 44 and 46 to create a very fine structure.

One of the features of this invention is the method of joining the bottom flashing 50 to the

apron 30 of the sill 16. Referring to Figure 3, the flashing 50 which is spot welded to a depending portion of the angulate member 46 has a central portion 58 bent forwardly and downwardly to form a flange 60 which is flush against the apron 30. The apron 30 and the flange 60 are spot welded and it is evident that water dropping from the sill 16 must fall from the dripping edge 62 because it will not climb up the vertical wall 5 of the flange 60 and thence over to the flashing 50.

Attention is invited to the double vertical walls of the louver formed by the members 10 and 44 on the left hand side in Figure 1 and the members 12 and 46 on the right hand side. Spacing the two walls and forming them from this piece of metal makes it possible to assemble the vanes to the inner wall, such as 10, while spot welding through but two thicknesses of metal. This construction is superior to an alternative construction wherein the double vertical walls are not spaced but flush against each other with the facing strip 18 being merely an outwardly turned flange. While such a construction is possible and will provide the requisite strength, unless the double wall were made of two pieces of metal, it would be necessary to spot weld through three thicknesses of steel in order to attach the flanges. In consequence of this, the spot welds would appear on the outside of the louver and would be unsightly. By applicant's construction the only spot welds which can be seen from the exterior of the dwelling are those along the flanges, such as 20, 24 and 56, and the apron 30.

The spacing of the walls that make up each double wall has the further advantage of providing a support on both sides of the facing strips 18 and 20. As mentioned in the introductory portion of this disclosure, existing louvers simply 30 flange the inner wall, such as 10, over the front edges of the vanes so as to create pockets between the vanes and the facing strips. One of applicant's primary aims could be accomplished by having a double wall, the two components of 35 which were not spaced, and flanging the forward edge of the double wall outwardly to get the face strip 18. This, however, leaves the facing strip 18 unsupported on the outside and where clapboards are used, creates pockets for dirt and 40 leaves between itself and the clapboards.

Over the inner surface of the louver is a screen 64 which is fastened to the top and two side walls by lapping it over and utilizing angle irons, such as 66, see Figure 3. The screening is fastened to the sill on its upper or top side, see Figure 1, by the simple expedient of covering it with a strip, such as 68, and spot welding it to the sill 16.

Having thus described my invention, what I claim as new and desire to secure by Letters Patent of the United States, is:

1. A vertical wall louver comprising right and left vertical wall members connected at top and bottom by a lintel and a sill, the front edge of 65 the vertical wall members being flanged outwardly to form a facing strip and again flanged backwardly to form a supporting flange, a plurality of vanes mounted in parallel relationship between said vertical wall members, each vane sloping forwardly, elongated angulate members each having one side fastened to one of said flanges and the other wall of each angulate member extending outwardly from the louver to act as a 70 flashing, a top flashing member extending across the lintel and mounted on the two upper ends of

said elongated angulate members, and a bottom flashing extending beneath the sill and mounted on the lower ends of said elongated angulate members.

2. A vertical wall louver comprising right and left vertical wall members connected at top and bottom by a lintel and a sill, the front edge of the vertical wall members being flanged outwardly to form a facing strip and again flanged backwardly to form a supporting flange, a plurality of vanes mounted in parallel relationship between said vertical wall members, each vane sloping forwardly, elongated angulate members each having one side fastened to one of said flanges and the other wall of each angulate member extending outwardly from the louver to act as a flashing, a top flashing member extending across the lintel and mounted on the two upper ends of said elongated angulate members, a bottom flashing extending beneath the sill and mounted on the lower ends of said elongated angulate members, an apron depending downwardly from the sill, and a portion of the lower flashing extending forwardly to engage the underside of the sill at points above the bottom of the apron whereby water flowing over the apron will be unable to reach the flashing.

3. A vertical wall louver comprising right and

left vertical wall members, the front edge of each of said members being flanged to form a facing strip and again flanged backwardly to form a supporting flange, a lintel member holding the upper ends of the two vertical wall members in assembled relationship, a plurality of vanes disposed in parallel relationship between said vertical wall members and sloping forwardly, the bottom edge of each vertical wall member being substantially parallel to the slope of said vanes, a sill member having its side edges flanged upwardly, said flanges being attached on the outer sides of said vertical wall members whereby the sill will act as a lowermost vane and direct water forwardly without seepage at the ends, a depending apron formed from the front edge of the sill, a vertical flashing mounted on the flange of each vertical member and set back from the facing strip, a top flashing extending over the lintel and mounted on the upper ends of the two vertical flashings, and a bottom flashing mounted on the lower ends of the vertical flashings and having an upper forwardly extending portion meeting the inner upper end of the depending apron and joined thereto by a downwardly directed flange.

FREELAND H. LESLIE.
